(57) **CLAIM**

The ornamental design for a portion of an image for a display screen, as shown and described.

DESCRIPTION

The FIGURE is a front view of a portion of an image for a display screen showing my new design.

The area defined within the broken line rectangle near the center of the icon is not a part of the claimed design. The broken line drawing of a display screen is for illustrative purposes only and forms no part of the claimed design.

1 Claim, 1 Drawing Sheet
